TRANSPORTABLE ANCHORABLE
REFRIGERATORHenry W. Blake, Kansas City, Mo., assignor to
William F. Kirk, Kansas City, Mo.

Application May 8, 1936, Serial No. 78,726

7 Claims. (Cl. 188—6)

This invention relates to transportable anchorable refrigerators or ice boxes adapted particularly for use in connection with the transportation of perishables in amounts less than car lot quantities, and the primary object of the invention is to provide anchoring means for refrigerators of the aforementioned character that will secure the same in place within a box car or truck body and preclude its accidental movement as the car or truck is traveling from place to place.

One of the important aims of this invention is to provide, in a refrigerator of the aforementioned type, anchoring means that will be effective in engaging the supporting surface or floor of the car within which the refrigerator is being transported and which may be moved to and from the operative position by manually manipulating certain parts of the anchoring mechanism.

A yet further aim of this invention is to provide anchoring mechanism for transportable refrigerators, having means for moving the anchoring elements thereof to and from an operative position, all of which is confined within the limits of the refrigerator case to the end that no protruding parts are presented to occupy space or engage freight that may be packed in a car with the refrigerator.

A still further and important object of the instant invention is to provide novel anchoring means for transportable anchorable refrigerators which comprises a number of anchoring elements, all mounted upon a common member, 35 movable therewith and yet independently movable to a limited degree, whereby to compensate for irregularities found in the supporting surface.

Another object of this invention is the provision in anchoring mechanism for refrigerators of the type mentioned, of structure for absorbing shock that might be imparted to the anchors, which structure is in the form of an abutment always in proximity to the anchoring elements 45 regardless of their position about their axis of rotation.

Still another object of the invention is to provide a refrigerator with anchoring means having a specially formed surface-engaging foot that will transmit the force tending to move the refrigerator in one direction to the case of the refrigerator, whereby to require such force to be absorbed by the action of gravity upon the case.

Other very important objects of the invention 55 will appear during the course of the following

specification, referring to the accompanying drawings, wherein:

Figure 1 is an end elevation of a transportable anchorable refrigerator embodying this invention.

Fig. 2 is a side elevation thereof.

Fig. 3 is a fragmentary, inverted plan view of the refrigerator.

Fig. 4 is an enlarged, fragmentary, detailed, sectional view, showing one of the anchoring elements and spring.

Fig. 5 is another enlarged, detailed, fragmentary, sectional view through a portion of the refrigerator case, showing the disposition of the operating lever, and.

Fig. 6 is a fragmentary, detailed, sectional view, illustrating an anchoring element of a character other than that shown in Figs. 1 to 5-inclusive.

The refrigerator or ice box is of a more or less conventional type in that it comprises a case 8, provided with doors 10 at one end thereof, by means of which the perishable goods may be moved to and from position within case 8. Wheels or rollers 12 and 14 are provided on the bottom of case 8 so that the refrigerator is rendered mobile to permit movement of the same to and from positions within a box car or truck during the handling and transportation. Wheels 12 are of the usual type, while rollers 14 should be of the "tiller" type in order to facilitate turning of the refrigerator during placement.

The refrigerator is usually moved into a box car or truck and placed in one corner so that the end wall of the freight car or truck, not here shown, will preclude movement of the refrigerator in one direction. The anchoring mechanism built into the refrigerator, therefore, need be at one end only thereof, but this invention obviously contemplates the employment of such mechanism at both ends of case 8 of the refrigerator.

A shaft 16 is rotatably journaled in bearings 18, which in turn are rigidly secured to the bottom of case 8. A number of anchoring elements 20 are carried by shaft 16 in a special manner so as to permit each of the several elements 20 to assume an individual angle of inclination. Supporting surface 22 may be the floor of the freight car or truck and this floor oftentimes presents irregularities so that if anchoring elements 20 were mounted rigidly upon shaft 16, one or more of said elements would be held off of surface 22 and therefore rendered ineffective.

To fulfill this feature of the invention, each anchoring element 20 has an integral wall 24

and bearing 26. Bearing 26 is provided with a slot 28 and a pin 30 integral with shaft 16 and projecting laterally therefrom through slot 28 permits a limited amount of movement of anchoring element 20 about shaft 16 independently thereof. Thus a more or less "floating" condition is presented that will permit compensation for supporting surface irregularities.

A spring 32, having one end joined as at 34 to the depending wall of case 8 and the other end secured to part 24 of anchoring element 20, yieldably urges the sharpened end of anchoring element 20 toward supporting surface 22.

Reference to Fig. 4 will readily teach that anchoring elements 20 engages shafts 16 intermediate the ends thereof and spring 32 has its connection rearwardly of the longitudinal axis of shaft 16. The movement of anchoring element 20 about the axis of shaft 16 is limited partly by a stop 36 that engages abutment 38 when the anchoring element is traveling in one direction about shaft 16. This abutment is in the nature of a strip of metal rigidly secured to the lowermost edges of the depending sides of case 8, and one edge of said abutment 38 is always in close proximity to the arcuate end 40 of wall 24 which forms an integral part of anchoring element 20. Arcuate end 40 is concentric with shaft 16 and as said element 20 travels around the center of shaft 16, end 40 is always close enough to the edge of abutment 38 to insure that abutment 38 will engage arcuate end 40 in the event force is exerted upon anchoring element 20 by the tendency of case 8 to move in one direction so that the sharpened end of anchoring element 20 engages surface 22. Thus a vast amount of force that would otherwise be absorbed by shaft 16 is taken up by abutment 38 and the less rugged parts of the anchoring mechanism are thereby relieved of unnecessary strain.

The means for moving anchoring elements 20 to and from the operative position illustrated in Figs. 2 and 4 is, in the example shown, merely a lever 42 secured to shaft 16 through the medium of one of the anchoring elements 20, so that the lever, anchoring elements and shaft 16 may all be simultaneously moved about the longitudinal axis of said shaft. When anchoring elements 20 are in engagement with the supporting surface 32, lever 42 is secured against movement in one direction by a detent 44 and when the lever is in a position with anchoring elements 20 out of engagement with supporting surface 22, another similar detent 46 is brought into play. Thus lever 42 and all of the anchoring mechanism may be manipulated so as to hold the anchoring elements in or out of the operative position.

An important point of this invention lies in the disposition of lever 42. No tools, cranks or similar instruments are necessary in moving the anchoring elements to the operative or inoperative positions. Furthermore, no part of the anchoring mechanism projects beyond the sides of case 8. A cavity 48, provided in one side of case 8, houses the upper end of lever 42 so that it may be conveniently reached by the operator. There is no probability, therefore, of freight that might be stored with the refrigerator being damaged by contact with projecting parts.

Another form of anchoring element is illustrated in Fig. 6. This particular form exemplifies the manner in which some of the important principals with respect to absorption of force may be built into the anchoring mechanism.

In this particular instance, case 8 carries the

shaft 16 as hereinbefore described and the operating lever 42 may be as mentioned. Anchoring element 50 per se, however, is specially formed to present a surface-engaging foot 52, having an arcuate face 54 that is concentric with the axis of shaft 16. A plurality of spurs 56 are on face 54. A part 58 of element 50 extends to the opposite side of shaft 16 and engages a stop 60 so as to limit the movement of element 50 in one direction about the axis of shaft 16. A spring 62, having one end angled to case 8 and the other joined to part 58, urges surface-engaging foot 52 toward the operative position.

The form of anchoring element 50 is therefore such as to lift case 8 when force is exerted thereagainst in the direction of the arrow. This force is thereby absorbed by the action of gravity which tends to hold case 8 upon surface 22 and a slight amount of rocking may take place to absorb the force when an anchoring element of this type is employed. In so absorbing the force, surface 22 is not destroyed or marred to as great an extent as when anchoring element 20 is employed. If the force tending to move case 8 in the direction of the arrow is greater than might be absorbed by the slight lifting of case 8 by the movement of member 50 about the axis of shaft 16, case 8 will continue to travel in the direction of the arrow until part 58 and stop 60 come into engagement. Thereafter spurs 56 will be forced into surface 22 so as to stop such movement and the action thereafter will be precisely the same as that of element 20. Obviously, the relative positions of stop 60 and part 58 are such as to preclude the movement of foot 52 rearwardly to a point where it no longer may engage surface 22.

Because of the scope of the spirit of this invention, it is known that the same may be embodied in many structures other than those herein described and illustrated and it is desired to be limited only by the appended claims.

Having thus described the invention, what is claimed as new and desired to be secured by Letters Patent is:

1. In a refrigerator of the character described, a case having a cavity formed in one side thereof; a plurality of rollers on the case for rendering the same mobile; anchoring elements movable to and from a position in engagement with the supporting surface; and operating mechanism for so moving the anchoring elements, said anchoring elements having yieldable means for urging the same against the said supporting surface when the operating mechanism has moved the said elements to the position in engagement with the said supporting surface, said anchoring elements being attached to the operating mechanism by means permitting limited movement of the elements independently of the said operating mechanism.

2. In a refrigerator of the character described, a case having a cavity formed in one side thereof; a plurality of rollers on the case for rendering the same mobile; a shaft mounted for oscillation on the bottom of the case; anchoring elements carried by the shaft for movement to and from a position in engagement with a supporting surface; and a lever for oscillating the shaft projecting upwardly into said cavity, said anchoring elements each having a bearing provided with a slot journaling the shaft, said shaft having a laterally extending pin projecting through said slot whereby to permit limited movement of the anchoring elements independently of the said shaft.

3. In a refrigerator of the character described, a case; a plurality of rollers on the case for rendering the same mobile; a shaft mounted for oscillation on the bottom of the case; a plurality of anchoring elements carried by the shaft for movement to and from a position in engagement with a supporting surface; means for so moving the anchoring elements; yieldable means for maintaining the said elements in engagement with the supporting surface; and an abutment on the case adjacent to the anchoring elements for engagement therewith when force is exerted against the anchoring element in one direction.
4. In a refrigerator of the character described, a case; a plurality of rollers on the case for rendering the same mobile; a shaft mounted for oscillation on the bottom of the case; a plurality of anchoring elements carried by the shaft for movement to and from a position in engagement with a supporting surface; means for so moving the anchoring elements; yieldable means for maintaining the said elements in engagement with the supporting surface; and an abutment on the case adjacent to the anchoring elements for engagement therewith when force is exerted against the anchoring element in one direction, said anchoring elements each having a stop for limiting the movement of said shaft and elements about the axis of said shaft.
5. In a refrigerator of the character described having a case with wheels thereon for rendering the same mobile, a shaft; bearings journalling said shaft on the bottom of the case; an anchoring element on the shaft extending to each side of the shaft; and an abutment on the case adjacent one end of said element for engagement therewith when force is exerted against the anchoring element in one direction.
6. In a refrigerator of the character described having a case with wheels thereon for rendering the same mobile, a shaft; bearings journalling said shaft on the bottom of the case; an anchoring element on the shaft extending to each side of the shaft; and an abutment on the case adjacent one end of said element for engagement therewith when force is exerted against the anchoring element in one direction, said abutment and anchoring element being formed to maintain a constant degree of proximity throughout the path of movement of the said element.
7. In a refrigerator of the character described having a case with wheels thereon for rendering the same mobile, an anchoring element pivotally mounted on the bottom of the case for movement to and from a position in engagement with the surface supporting the refrigerator to preclude appreciable movement in one direction; a surface-engaging foot on the anchoring element having an arcuate face eccentric to the axis of rotation of said anchoring element whereby when force is exerted upon the case in one direction the same is raised by the said anchoring element; a spring to yieldably maintain the arcuate face of said element in engagement with the supporting surface; spurs formed on the arcuate face of said foot; and a stop for limiting the movement of the foot about the axis of the pivotal mounting of the anchoring element whereby after a relatively small amount of movement in one direction the said element ceases to raise the case and the said spurs engage the supporting surface to preclude skidding or further movement in the aforesaid one direction.

HENRY W. BLAKE.
